(57) **CLAIM**

We claim the ornamental design for a mobile device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a first embodiment of a mobile device, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and

FIG. 7 is a bottom plan view thereof.

FIG. 8 is a perspective view of a second embodiment of a mobile device, showing our new design;

FIG. 9 is a front, right side perspective view thereof;

FIG. 10 is a right side elevation view thereof;

FIG. 11 is a rear elevation view thereof; and

FIG. 12 is a left side rear perspective view thereof.

FIG. 13 is a perspective view of a third embodiment of a mobile device, showing our new design;

FIG. 14 is a front, right side perspective view thereof;

FIG. 15 is a right side elevation view thereof;

FIG. 16 is a rear elevation view thereof; and,

FIG. 17 is a left side rear perspective view thereof.

The outermost broken lines immediately adjacent the claim, encompassing regions blocked out by white or grey, represent the bounds of the claimed design while all other broken lines are directed to environment and are for illustrative purposes only; the broken lines form no part of the claimed design.

The logo in the Embodiments forming part of the disclosure is a registered trademark of RAZER (ASIA-PACIFIC) PTE. LTD.
